H. E. THOMPSON

PROCESS OF MAKING GASOLINE

Original Filed Aug. 29. 1921

Inventor:

Harold E. Thompson,

By *Bynes, Townsend & Pickerington*,

Attorneys.

UNITED STATES PATENT OFFICE.

HAROLD E. THOMPSON, OF CLENDENIN, WEST VIRGINIA, ASSIGNOR TO CARBIDE & CARBON CHEMICALS CORPORATION, A CORPORATION OF NEW YORK.

PROCESS OF MAKING GASOLINE.

Original application filed August 29, 1921, Serial No. 496,321. Divided and this application filed September 8, 1922. Serial No. 586,811.

To all whom it may concern:

Be it known that I, HAROLD E. THOMPSON, a citizen of the United States, residing at Clendenin, in the county of Kanawha and State of West Virginia, have invented certain new and useful Improvements in Processes of Making Gasoline, of which the following is a specification.

This invention relates to the manufacture, from natural gas, of liquid mixtures of hydrocarbons adapted for use as motor fuel and for other purposes. An example is the liquid commonly known as natural gas gasoline, natural gasoline, casing-head gasoline, etc. The object of the invention is to improve the processes for making such liquids and to improve the products obtained.

This application is a division of my co-pending application, Serial No. 496,321, filed August 29, 1921, which matured into Patent No. 1,429,175, dated Sept. 12, 1922.

Natural gases are essentially mixtures of paraffin hydrocarbons. Only the lower members of the paraffin series are present, and the percentages of the individual hydrocarbons present usually bear an inverse relation to their molecular weights. Methane always predominates, and in some gases the content of other members of the series is negligible. Those natural gases which are adapted for the production of gasoline, however, contain considerable quantities of ethane, propane, butane and the heavier hydrocarbons, and it is with such naturally occurring mixtures that the invention is concerned.

In the natural gas or casing-head gasoline industry, the desideratum is to produce a liquid which can be transported and stored at ordinary temperatures and at or near barometric pressure, in receptacles similar to those used for straight-run gasoline, without undue fire risk or loss by evaporation. In other words, the problem is to keep down the volatility of the product, as evidenced by the vapor pressure of the liquid at certain temperatures. A high yield is of course desirable.

Partially because of lack of knowledge of the compositions of the natural gas used as raw material and of the products and by-products obtained, the process as now carried out is largely empirical. As the process is practised, a preliminary product is obtained which is so volatile, or "wild", that it cannot be safely stored or shipped. The volatility of this liquid is ordinarily reduced by the wasteful process known as "weathering", which consists in storing the liquid in open tanks or tanks maintained at a low pressure and permitting spontaneous evaporation to go on until a sufficiently stable residue remains. This results in the loss in the aggregate of enormous quantities of hydrocarbon material suitable for gasoline.

By the application of improved methods of analysis, I have found that the excessive volatility or "wildness" of freshly made casing-head gasoline is due to the presence of ethane and propane. Even methane may be present in traces at times. Butane, which in pure form has a much greater volatility than is permissible in merchantable gasoline, can be present in casing-head gasoline in large proportions, up to the entire butane content of the gas treated, without excessive "wildness" of the product because of the solvent effect of the heavier hydrocarbons present upon it. I have found that in the natural weathering process a large proportion of the butane passes off before the residue is sufficiently stable. When this condition is reached, propane and even ethane are still present in the residue, while the butane may have been evaporated and lost in amount in large proportion as compared with the residual liquid.

My invention comprises a rational treatment of material containing the less volatile portions of natural gas, whereby the material is separated into fractions which do not have more than one common ingredient in substantial quantity. As mentioned above, the natural weathering process produces a vapor containing ethane, propane,

large amounts of butane, and even heavier hydrocarbons, while the residual liquid contains substantial quantities of all these compounds. By my process, I am able to expel substantially all the ethane and propane as vapor while volatilizing only a small quantity of butane, thus producing a gasoline of as good or better grade than can be made by natural weathering and at the same time very largely increasing the yield. In many cases I prefer to evaporate a portion of the butane and thus produce a higher-grade or less volatile gasoline, but in such cases butane will be the only hydrocarbon present in substantial quantity as a common ingredient in both the expelled vapor and the liquid residue. Even when a portion of the butane is expelled, the product is readily distinguishable from all petroleum distillates employed in the gasoline industry, as these latter contain a much smaller proportion of butane. All the butane might be vaporized, or a portion of the propane might be retained in the residue if desired. Depending on the identity of the hydrocarbon which is the highest of those in the vaporized portion and the proportion of that hydrocarbon which is evaporated, the vapor pressure of the liquid residue may be adjusted to any desired value.

Certain procedure in the process now to be described is referred to in the specification and claims as "rectification". The term "rectification" is used herein to describe a process wherein a liquid is boiled, the vapor produced is caused to contact with a second body of liquid of different composition in such manner that a second portion of vapor is evolved from the second body of liquid, the second portion of vapor contacts with a third body of liquid which likewise evolves vapor, and so on through a sufficient number of vapor and liquid contacts. Liquid flows from one body to the next in a direction counter to that of the vapor flow, and the continuity of the process is maintained by adding liquid to the body from which the final portion of vapor is evolved, the liquid so added being formed, for example, by partial condensation of the final vapor. The uncondensed portion of the final vapor, and a continuously-withdrawn portion of the boiling liquid first referred to, are ordinarily the products sought. It is only with such systematic processes involving repeated liquid and vapor contacts in a series of distinct phases, that the present invention is concerned.

A complete separation of certain constituents of gas mixtures has sometimes been attempted by a fractional condensation. I have found that complete separation cannot be accomplished in this way. In any fractional liquefaction process the initial con-

densing brings down some of the more volatile constituents which in my process I then remove by boiling and rectification.

For a better understanding of the invention, reference will be made to the accompanying drawing, comprising a diagrammatic illustration of one method of applying my invention.

A typical natural gas gasoline process will now be described in connection with the drawing, and the manner in which the process of my invention may be applied thereto will be indicated. The process now to be described is of the type usually designated an "absorption process".

Gas from one or more wells is subjected to a pressure of 250-300 lbs. per square inch by compressor 4 and cooled in the cooler 5 to approximately atmospheric temperature. The heavier hydrocarbons present, usually contaminated by lubricating oil and by petroleum suspended in the gas, will condense and may be withdrawn at 6 for further treatment. The gas, still under pressure, is then passed to the water-cooled absorber 7, where it is brought into contact with an oil of the kind commonly employed for this purpose. The undissolved gas is passed from the absorber to the main 8 while the oil with its dissolved hydrocarbons flows to vent-tank 9 where the pressure on the oil is released by a suitable regulator 9^a.

In tank 9, a pressure of about 60 lbs. per square inch is maintained and as the oil under high pressure flows into it, a large volume of gas comprising the lighter dissolved constituents is liberated. Using a natural gas of the following composition:

	Per cent.	105
Methane	78.3	
Ethane	13.3	
Propane	5.6	
Butane and less volatile bodies	2.8	

the composition of the gases so liberated may be, for example, as follows:

	Per cent.	110
Methane	50.1	
Ethane	29.8	
Propane	16.7	
Butane and less volatile bodies	4.3	

This gas mixture will be referred to, for convenience, as "high-pressure vent gas."

From tank 9 the oil with the substances dissolved therein passes to vent tank 10, in which 3 to 4 lbs. gage pressure may be maintained. The pressure on the oil is released by a suitable regulator 10^a. The reduction in pressure causes an additional evolution of gases which comprise, in general, hydrocarbons heavier than those which constitute the high-pressure vent gas but of greater volatility than the constituents which remain dissolved in the oil. The analysis of

the gas liberated in tank 10 may be, for example:

	Per cent.
Methane	14.6
Ethane	36.0
Propane	36.4
Butane and less volatile bodies	13.0

and this gas will be termed "low-pressure vent gas."

From tank 10 the oil passes to heat exchanger 11 and thence to still 12 where it is blown with live steam, the result being that practically all the substances remaining in the oil are expelled. The mixture of steam and hydrocarbons formed in the still passes to condenser 13 maintained at a temperature somewhat below the boiling point of water. In this condenser most of the aqueous vapor is condensed and is withdrawn through trap 14, but the hydrocarbons remain in vapor state as does also a considerable amount of water. The oil from still 12, after being freed from dissolved substances, returns through heat-exchanger 11 to absorber 7 after being cooled by water.

The hydrocarbon vapors pass from condenser 13 to the precooler 15, where they are cooled to substantially atmospheric temperature with the condensation of the heavier hydrocarbons present and most of the remaining water. The liquid formed in the precooler is drawn off into storage tank 16, where the water is separated from it in any suitable way. The liquid in tank 16 will be referred to as the "precooler liquid". It may have, for example, the following composition:

	Per cent by weight.
Ethane	0.1
Propane	2.0
Butane	9.0
Pentane and less volatile bodies	88.9

Vapors not condensed in the precooler pass to a compressor 17, where their pressure is raised to about 50 lbs., and then to another cooling unit 18, where they are again brought to atmospheric temperature. This cooling unit is termed the "intercooler". The condensed liquid is drawn into the storage tank 19 and is termed the "intercooler liquid". It may have, for example, the following composition:

	Per cent by weight.
Methane	0.1
Ethane	0.7
Propane	10.0
Butane	52.3
Pentane and less volatile bodies	36.9

The vapors from the intercooler pass into compressor 20, where the pressure is further increased to, say, 150 lbs. per square inch, and then to a third cooling unit 21 which is

also cooled to atmospheric temperature. This latter cooler is known as the "aftercooler" and it likewise produces a condensate, which collects in tank 22, known as the "aftercooler tank", the liquid collecting therein being termed the "aftercooler liquid". It may have, for example, the following composition:

	Per cent by weight.
Methane	0.3
Ethane	2.9
Propane	17.4
Butane	71.0
Pentane and less volatile bodies	8.4

A portion of the vapors still remain uncondensed by the aftercooler and they are herein termed, for convenience, "fixed gases". Their composition may be as follows:

	Per cent by volume.
Methane	5.2
Ethane	48.2
Propane	41.6
Butane and less volatile bodies	4.6

Absorption natural gas gasoline processes now in general use are similar in their general aspect to that outlined above. The low-pressure and high-pressure vent gases and the fixed gases are ordinarily used only as fuel. The precooler, intercooler, and aftercooler liquids are combined to produce the gasoline, the product being highly volatile and requiring a further treatment in order to fit it for use. This is accomplished by the natural weathering process already referred to, wherein the wild product is stored in tanks at low pressure until a portion of it has evaporated. By such procedure there is a total loss of the ethane, propane, butane and higher hydrocarbons which evaporate during weathering, while the butane in the high- and low-pressure vent gases and the fixed gases is not incorporated into the gasoline produced.

In accordance with my invention, substantially the entire quantity of butane which dissolves in the oil in the absorber 7 may be worked into gasoline, while the ethane and propane which escape to the air in the natural weathering process may be recovered. The manner in which this may be accomplished is as follows:

The precooler, intercooler and aftercooler liquids, the high- and low-pressure vent gases, and the fixed gases, are introduced at appropriate points into the rectifying column 23, the most volatile mixtures being introduced nearest the top and those most nearly approaching the volatility desired in the final product being led into the column near its base. The column is provided with trays 23^a which divide it into compartments, means being provided for

the downward flow of liquid and the upward passage of vapors, and the column is fitted with devices for drawing off water and for testing and regulation which need not be 5 described here.

Connected to the base of column 23 is a vessel 24 adapted to receive the liquid leaving the bottom of the column. The vessel 24 is provided with a heating coil 25, and a

10 vapor pipe 26 is arranged to lead vapors evolved in vessel 24 into the column 23. The liquid from the column passes through trap 27 to the vessel 24.

The various mixtures are introduced into 15 column 23 in the following order, beginning at the top: high-pressure vent gas, low-pressure vent gas, fixed gas, aftercooler liquid, intercooler liquid and precooler liquid. The last-named contains only small

20 amounts of hydrocarbons more volatile than butane, and requires but little rectification; while the high-pressure vent gas, having only 4.3% of butane, and less volatile bodies, requires the most thorough treat-

25 ment. The high- and low-pressure vent gases are compressed and cooled so that they enter the column in liquid phase, as subsequently described. The expansion of the mixtures into the upper part of the column absorbs

30 heat, while the temperature at the foot of the column is kept up by warm vapors entering through pipe 26. The temperature gradient necessary for rectification is thus maintained. The gasoline is withdrawn from

35 tank 24 at 29, continuously or at intervals.

The high-pressure vent gas and low-pressure vent gas pass through heat exchanger 31 on their way to the column, and therein are cooled, giving up their heat to the gases

40 from pipe 28 which flow through exchanger 31 in heat-interchanging relation to the vent gases. The high-pressure vent gas may be compressed in compressor 32, before it enters the heat exchanger 31, to such a

45 pressure that there will be a partial or complete liquefaction of this gas as it passes through the expansion valve 34 and enters the column 23. The pressure in column 23 may advantageously be about 9 lbs. gage and

50 may be maintained by the regulator 30. The pressure in vessel 24 is, of course, somewhat higher than at the top of the column because of the head of liquid on the trays 23^a. The pressure before expansion may be 800 to

55 1000 lbs. per square inch, depending on the proportion of liquefaction desired and the efficiency of the heat exchanger 31.

In a similar manner the low-pressure vent gas is compressed in compressor 33 to a 60 pressure which may be 600 to 800 lbs. per square inch before it enters the heat exchanger and is expanded from this pressure to column pressure through valve 35 wherein a partial or complete liquefaction may occur.

The fixed gas from the aftercooler may like- 65 wise be further compressed before expansion but in general this will be unnecessary to obtain the desired liquefaction at the expansion valve. The gases escaping at the top of column 23, consisting of constituents ex- 70 cluded from the gasoline, pass through the regulator 30 and may be used as fuel or for any other purpose.

The control of the process is very simple. If it is desired to change the quality of the 75 final product, this may conveniently be accomplished by varying the rate at which heat is supplied to vessel 24, the pressure in

the system remaining unchanged. More heat supplied will obviously result in the evapo- 80 ration of more material in unit time, and more vapors are released at 30 to keep down the pressure.

Since a larger proportion of material then enters the vapor fraction, the liquid fraction will decrease in quantity, and 85 since the hydrocarbons escaping at 30 are the most volatile of those entering the column, the volatility of the liquid fraction will be decreased. Furthermore, the vapor

pressure of the liquid product can be accurately predetermined from the conditions 90 under which the column is working, namely,

the pressure and the temperature of the vapors passing through line 26. These 95 vapors may be maintained, for example, at a temperature of from 70° to 90° F. In a particular instance when the vapors in pipe 26 had a temperature of 83° F., the material

produced had a vapor pressure of 8 lbs. at 100 70° F. and a vapor pressure of 14 lbs. at 100° F. By increasing the temperature of the vapor entering the column, the above

figures can be considerably reduced, but with a decreased yield of material. The composition 105 of the vapor fraction can of course be regulated as easily as that of the liquid, and by the same means.

While the above description shows the most complete utilization of all the gasoline 110 constituents removed from the natural gas by the absorbing oil, in many instances other embodiments of my invention will recom-

mend themselves on the grounds of their simplicity. A simplified embodiment of the 115 invention in which only the liquid condensates are subjected to rectification and in which exit gases from the rectification column are added to gas passing to the pre-

cooler, is described in the parent application referred to above and is claimed in the 120 patent into which said application matured.

Besides the absorption process, there is another principal type of natural gas gasoline 125 process, frequently styled the compression process, which is simpler in its general execu-

tion in that it does not involve an absorbing medium. In this process, the condensation is effected by compression and

cooling. The compression is usually accomplished in several stages and the cooling takes place between stages by means of suitable coils, condensers, etc. In this process the condensates are formed in the coolers after each compression stage and correspond very closely in their composition and further treatment to the condensates obtained in the absorption process described above, although in some cases there is no fraction corresponding to the precooler liquid. In the simplest case in which there is but one stage of compression, the condensate corresponds most closely to the "intercooler liquid" above. In the execution of my process there is no fundamental difference between the treatment of the liquid fractions obtained in the absorption process and those obtained in the compression process.

The product of my invention may, in some cases, differ from natural gas gasoline, prepared by prior process, in having relatively high gravity on the Baumé scale, varying from 87° to 92° Bé., and at the same time having a vapor pressure of from 10 to 12 lbs. at 100° F., which pressure is characteristic of ordinary natural gas gasoline of gravity from 72° to 84° Bé.

It will be noted that the execution of my process requires the use of only moderate pressures in the rectifying column, the pressures specifically mentioned herein being less than one atmosphere gage. Pressures of this order, viz not substantially in excess of one atmosphere, are sufficient to permit the upper portion of the rectifying column to be furnished with the necessary liquid material without special difficulty, for example by the expansion thereinto of hydrocarbon material which has been compressed and cooled, and the use of such low pressures simplifies the design of the column and cheapens its construction.

While I have described my invention in connection with certain particular ways of producing a series of mixtures containing the heavier hydrocarbons of natural gas, and in connection with certain series of mixtures of particular composition, this is done merely to illustrate the invention. My invention is equally applicable where a greater or less number of fractional mixtures are produced, and where the relative volatility of the various fractional mixtures is entirely different from what has been instanced. Furthermore, I am not limited to the treatment of any fixed number of the fractions produced in the preliminary treatment of the gas, but may treat only such of these as the circumstances in a particular case require. Any fraction which contains but little gasoline constituents may be discarded or utilized in other connections, while any fraction which is an acceptable material as a gasoline or

otherwise, without further treatment, need not go to the rectifying process. My invention is limited only by the appended claims.

I claim:

1. Process of making gasoline which comprises producing from natural gas a concentrate of its heavier hydrocarbons, separating from said concentrate a more volatile fraction and a less volatile fraction, rectifying said less volatile fraction in a rectifying column to produce a liquid and a vapor, compressing said more volatile fraction, cooling it by heat-interchange with the vapor from the less volatile fraction, and expanding the material so cooled into the rectifying column at a point above the place of introduction of said less volatile fraction.

2. Process of making gasoline which comprises producing from natural gas a concentrate of its heavier hydrocarbons, separating from said concentrate a more volatile fraction and a less volatile fraction, rectifying said less volatile fraction in a rectifying column at a pressure not substantially in excess of one atmosphere to produce a liquid and a vapor, compressing said more volatile fraction, cooling it by heat-interchange with the vapor from the less volatile fraction, and expanding the material so cooled into the rectifying column at a point above the place of introduction of said less volatile fraction.

3. Process of decreasing the volatility of wild natural gasoline which comprises rectifying the wild material in a rectifying column at a pressure not substantially in excess of one atmosphere to produce a liquid and a vapor; compressing natural gas hydrocarbons and cooling them by heat-interchange with said vapor; and cooling the upper part of the rectifying column by expanding into it the hydrocarbons so cooled.

4. Process of making gasoline which comprises producing from natural gas by absorption a concentrate of its heavier hydrocarbons, separating from said concentrate a more volatile fraction and a less volatile fraction, rectifying said less volatile fraction in a rectifying column to produce a liquid and a vapor, compressing said more volatile fraction, cooling it by heat-interchange with the vapor from the less volatile fraction, and expanding the material so cooled into the rectifying column at a point above the place of introduction of said less volatile fraction.

5. Process of making gasoline which comprises producing from natural gas by absorption a concentrate of its heavier hydrocarbons, separating from said concentrate a more volatile fraction and a less volatile fraction, rectifying said less volatile fraction in a rectifying column at a pressure not substantially in excess of one atmos-

6
phere to produce a liquid and a vapor, compressing said more volatile fraction, cooling it by heat-interchange with the vapor from the less volatile fraction, and expanding the 5 material so cooled into the rectifying column at a point above the place of introduction of said less volatile fraction.

6. Process of making gasoline which comprises treating natural gas under pressure 10 with an absorbent, separating the hydrocarbons taken up by the absorbent into more and less volatile fractions, producing from a less volatile fraction a liquid having a

higher volatility than that desired in the gasoline, rectifying said liquid at a pressure not substantially in excess of one atmosphere in a rectifying column to produce a still less volatile liquid and a vapor, and cooling the upper part of the column by compressing a more volatile one of said 15 fractions cooling the compressed material by heat-interchange with said vapor, and expanding it into the column. 20

In testimony whereof, I affix my signature.

HAROLD E. THOMPSON.
